PYROPHORIC IGNITER

Frederick Charles Wise and Willey Greenwood,
London, EnglandApplication May 29, 1935, Serial No. 23,962
In Great Britain February 20, 1935

5 Claims. (Cl. 67—7.1)

This invention relates to a pyrophoric igniter of the kind wherein a tube containing the flint and its controlling spring, is enclosed within the casing of the apparatus and is accessible through an opening in one of the walls thereof, the closing member for said opening serving as a support for the spring, and the invention consists essentially in the provision of a closing member in the form of a slide which is fitted in the casing wall so as to move across the wall and the opening.

The object of this arrangement is to obtain a closing member which is neater and at the same time more easily manipulated than the screw usually employed for this purpose.

The spring bears loosely against the slide, and means are provided for preventing the spring from being shot out of the tube when the slide is withdrawn.

20 Preferably the tube is arranged in a horizontal position in a chamber which also contains the wick tube and the abrasive wheel and which is closed in known manner by a hinged lid, the latter and the slide being made so as to be flush with the adjacent surfaces.

Fig. 1 of the accompanying drawing represents a perspective view of a pocket lighter constructed according to the invention.

Fig. 2 is another perspective view showing the slide in open position.

Fig. 3 is a sectional side view of the lighter drawn to a larger scale.

Fig. 4 is a sectional view of the spring tube showing the spring released, and

Fig. 5 is another sectional view of the tube showing the elements in operative position.

The illustrated lighter comprises a flat casing 1 the upper part of which is formed with a chamber 1a containing the upright wick tube 2 and a vertical spindle 3 whereon the abrasive wheel 4 and a milled operating head 5 are rotatably mounted. The head 5 projects through a slot in the casing in known manner. One side wall of the casing is partly cut open so as to give free access to the flame, and the cut-off portion is replaced by a side piece 6 connected in known manner to a hinged lid 7 whereby the casing is normally closed. The lid is controlled by a leaf spring 8 and is fitted in known manner with a spring-controlled cap 9 which normally bears against and closes the wick tube.

The flint 10 (Fig. 5) and the spring 11 by means of which it is held against the abrasive wheel 4, are enclosed in a tube 12 which is arranged in a horizontal position in the chamber

1a and which is accessible through an opening 13 in one of the narrow walls of the casing 1. This opening is normally closed by a slide 14 which forms an abutment for the spring and which is withdrawn as shown in Fig. 2 for uncovering the opening.

To prevent the spring 11 from being shot out of the tube when the supporting slide is withdrawn, the following arrangement is provided: the spring is connected in known manner, at 10 one end to a plunger 15 by means of which it bears against the flint 10, and at the other end to a head 16. The plunger is provided with a flange 17 which fits the tube 12 snugly and which co-operates with a radially projecting pin or 15 screw 18 fitted in the wall of the tube for checking the outward movement of the spring when the slide 14 is withdrawn. In order to allow a complete withdrawal of the spring from the tube, the flange 17 is provided with an oblique 20 nick 19 which forms a gateway for the projection 18 and allows the flange to pass when, in addition to being pushed or pulled, it is subjected by means of the spring and the head 16, to a rotary motion.

The tube has a reduced portion in which the plunger 15 and the flint 10 are guided, and the shoulder formed by the reduced portion serves as an abutment for the flange 17 which thus prevents the plunger from coming into contact with 30 the abrasive wheel 4 when the flint is worn out. This is illustrated in Fig. 4. The head 16 is provided with a flange 20 which is normally accommodated in a recess in the tube and which prevents the spring from being inserted the wrong 35 way into the tube. A reduced end portion 21 on the head 16 serves as a means for facilitating the replacement of the head under the slide. By pressure applied to the portion 21, the spring can be compressed sufficiently for the slide to 40 engage over the main portion of the head, whereupon it is easy to slip the remaining portion under the slide.

To prevent the slide from being completely withdrawn from the casing, a pin or screw 22 in 45 the casing behind the slide and adapted to engage in a groove in the latter.

An additional tube 23 may be arranged under the tube 12 for the reception of spare flints. This tube is accessible through an opening 23' which is 50 also closed by the slide.

As is evident from Figs. 1 and 2, the slide 14 and cover 7 can be made so as to be flush with the adjacent surfaces, and the casing need not, therefore, have normally any other projection 55

than that of the milled head 5. Moreover, if neatly fitted, and particularly if it participates in the ornamentation of the casing, the slide can be rendered quite inconspicuous.

5. We claim:

1. A pyrophoric igniter comprising a casing, a flint tube enclosed in said casing and accessible through a wall thereof, a flint actuating spring in said tube, a slide in the casing wall carried transversely across the latter and forming a closure for the tube and an abutment for said spring, a plunger connected to the spring for engagement with the flint, a flange on said plunger, and a stop in the tube adapted to co-operate with said flange for retaining the spring normally within the tube, said flange having an inclined nick serving as a gateway for the stop.

2. The structure claimed in claim 1 in combination with a head connected to the spring for engagement with the slide, said head being made larger than the bore of the tube and recessed into the latter.

3. A pyrophoric igniter comprising a casing having a top chamber, igniting elements in said chamber comprising a flint tube arranged in a horizontal position and accessible through a side wall of the casing, a flint actuating spring in said tube, a slide in the casing wall

carried transversely across the latter and forming a closure for the tube and an abutment for said spring, means for limiting the movement of the slide, and checking means for the spring operative to prevent it from being shot out of the tube when the slide is withdrawn and to release the spring for complete extraction on the rotary displacement thereof.

4. A pyrophoric pocket lighter comprising a flat casing having igniting elements accommodated in a chamber at one end of said casing, a hinged lid covering said chamber, said igniting elements comprising a flint tube which is accessible through a narrow side wall of the casing, a flint actuating spring in said tube, a slide fitted horizontally in said narrow side wall as a closure for the tube and as an abutment for said spring, and checking means for the spring operative to prevent it from being shot out of the tube when the slide is withdrawn and to release the spring for complete extraction on a rotary displacement thereof.

5. A structure as claimed in claim 4 wherein the lid and the slide are flush with the adjacent portions of the casing.

FREDERICK CHARLES WISE.
WILLEY GREENWOOD.
